Primary Examiner — April Rivas*Assistant Examiner* — Jillian Mazzola(74) Attorney, Agent, or Firm — Fitzgerald IP Law; John K. Fitzgerald, Esq.(57) CLAIM

The ornamental design for a case for toy beads, as shown and described.

DESCRIPTION

FIG. 1 is a perspective view of the front, top, and right sides of a case for toy beads showing my new design; FIG. 2 is a perspective view of the rear, bottom, and left sides thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof;

FIG. 8 is a left side view thereof; and,

FIG. 9 is a perspective view of the case for toy beads shown in an alternate configuration showing the interior of the article.

The broken lines shown are included for the purpose of illustrating portions of the case for toy beads that form no part of the claimed design.
